UNITED STATES PATENT OFFICE.

MARION DEE SMITH, OF CASPER, WYOMING, ASSIGNOR OF ONE-HALF TO CLARENCE E. ROSS, OF FORT WORTH, TEXAS.

BOILER-CONTROL DEVICE.

Application filed September 13, 1924. Serial No. 737,615.

This invention relates to boiler control devices, and more particularly to a device of this character adapted to control the supply of feed water to the boiler.

5 An important object of the invention is to provide a device of this character which, in addition to controlling the supply of feed water to the boiler, also controls the supply of fuel to the boiler, so that in event of the 10 water becoming dangerously low in the boiler this fuel supply is cut off.

A further object of the invention is to provide a device of this character in which the control of the feed water supply is obtained 15 by the control of the steam supply to the feed water pump and not by any control of the feed of any water either to or from the feed water pump, it having been found by experiments that this results in a steam 20 bound pump, particularly where the cut-off valve is employed in the suction line, as it must be unless dangerous pressure is to be brought to bear against the heads of the steam end of the pump.

25 A still further object of the invention is to provide a device of this character which is extremely simple in its construction and operation, which may be readily applied, and which will be durable and efficient in service.

30 These and other objects I attain by the construction shown in the accompanying drawings, wherein for the purpose of illustration is shown a preferred embodiment of my invention and wherein:—

35 Figure 1 is a side elevation showing a feed water control device constructed and connected in accordance with my invention, a portion of the control being broken away;

Figure 2 is a transverse sectional view 40 therethrough.

Referring now more particularly to the drawings, the control consists of a vertical float chamber 10 having in its lower end an inlet 11 and in its upper end an outlet 12, 45 one side of this pump chamber being made removable, as indicated at 13, so that the float may be inspected and repaired when necessary. At the opposite side of the chamber a reduced triangular extension 14 is provided having its base abutting the float chamber and having at its apex 15 and in the side walls of such apex a pair of bearings receiving a shaft 16, these bearings being of the packing type as illustrated at 17. 50 Upon the shaft within the extension 14 is

mounted the hub end 18 of an arm 19, the opposite end of which is provided with a float extending into the float chamber 10. The ends of the shaft project beyond the sides of the triangular extension 14 for a 60 purpose presently to appear.

In the use of the device, which is conveniently located at any point adjacent the boiler and feed water pump (not herein shown), the inlet 11 is connected to the 65 boiler below the water line thereof, as indicated, while the outlet 12 is connected to the boiler above the water line and preferably at the steam dome as indicated. Upon one end of the shaft an arm 20 is secured intermediate its ends, one end of this arm being provided with an adjustable weight 21 and the opposite end thereof is connected with a balanced cut-off valve 22 located in the steam line to the feed water pump. Upon the 70 opposite end of the shaft 16 is secured one end of an arm 23, the opposite end of which is operatively connected with the latch 24 of a latch valve 25 located in the fuel line 75 to the boiler.

The operation of the device, when connected as above and properly adjusted, is as follows: As long as the water in the boiler remains at the proper level, the float is stationary and neither of the valves 22 or 25 80 are in any way affected. As the water falls below the proper level, a steam line valve is opened causing the pump to come in operation and supply feed water to the boiler. In event the pump fails or for any other reason 85 the boiler water continues to lower, before it reaches the dangerous point the latch valve 25 is operated and the fuel line to the boiler closed. It will thus be seen that all 90 danger in operation to the boiler on account of failure of the water thereof is eliminated, the feed water pump at ordinary times operating to supply the water and upon failure of the feed water pump the fires of the boiler 95 being extinguished.

It will be obvious that the type of valves employed is capable of a considerable range of change and modification without materially departing from the spirit of my invention, and I accordingly do not limit myself 100 to such specific structure as hereinbefore set forth except as hereinafter claimed.

I claim:—

110 In combination with a boiler having a fuel feed line and a feed water pump sup-

plying water to the boiler, a chamber arranged exteriorly of the boiler connected with the boiler above and below the water line thereof, a float operating within the chamber, a shaft rocked by the rise and fall of the float, a feed line for the feed water pump, a cut-off valve in said feed line, an adjustable connection between said shaft and said valve closing the valve upon elevation of the float, a self-closing latch valve in

the fuel line to the boiler, and means operatively connecting the valve and said shaft operating to release the latch of the latch valve and permit the latch valve to close upon a predetermined lowering of the float 15 within the chamber.

In testimony whereof I hereunto affix my signature.

MARION DEE SMITH.
